CLAIM

The ornamental design for a footwear upper, as shown and described.

DESCRIPTION

FIG. 1 is a perspective view of a footwear outsole according to my new design;

FIG. 2 is a front view thereof;

FIG. 3 is a rear view thereof;

FIG. 4 is a right side view thereof;

FIG. 5 is a left side view thereof; and,

FIG. 6 is a bottom view thereof.

The broken lines shown on the shoe upper, including the single, double, and triple rows of broken lines, as well as the broken zig zag pattern, represent stitching that forms a part of the claimed design. The broken lines in the figures forming the midsole and outsole structure indicate environment and form no part of the claimed design.
